UNITED STATES PATENT OFFICE.

WILLIAM H. GAILOR, OF SARATOGA SPRINGS, NEW YORK.

MACHINE FOR DISTRIBUTING FLUID ROAD MATERIAL.

1,159,343.

Specification of Letters Patent.

Patented Nov. 2, 1915.

Application filed March 9, 1914. Serial No. 823,370.

To all whom it may concern:

Be it known that I, WILLIAM H. GAILOR, a citizen of the United States, residing at Saratoga Springs, in the county of Saratoga and State of New York, have invented certain new and useful Improvements in Machines for Distributing Fluid Road Material, of which the following is a specification.

This invention relates to improvements in machines for distributing bituminous and other binding material upon roadways, and it comprises an improved arrangement of distributing pipes and other features of construction, the details and advantages of which will be clear from the following specification taken in connection with the accompanying drawing, in which,

Figure 1 is a top plan view of a distributing vehicle embodying my improvements, the distributing pipes being lowered and the lateral adjustments of the pipes being illustrated in dotted lines; Fig. 2 is a side elevation of the same, the vertical adjustments of the pipes being illustrated in dotted lines; Fig. 3 is a rear elevation of the same, the distributing pipes being partly broken away; Fig. 4 is a detail view showing the connections between the two portions of the valve operating rod; Figs. 5 and 6 are side and rear elevations, respectively, and Fig. 7 is a top plan view of a modified arrangement of distributing pipes.

Referring to Figs. 1 to 4, inclusive, of the drawing, *a* indicates the vehicle frame, *b* the wheels, and *c* the axle. The central portion 1 of the axle, as shown, is curved downwardly, being semi-cylindrical in form, and forms a saddle for supporting a horizontally arranged cylindrical tank *d* which rests upon it. This tank is adapted to contain the fluid which is to be spread upon the roadway. The end portions 2 of the axle are substantially horizontal. The frame comprises side bars 3 extending parallel with the sides of the tank *d* and resting upon the end portions of the axles, these bars having converging extensions 3^a which project forwardly from the tank, the ends 3^b of these converging portions being riveted or bolted together through a spacing block 4, having a downwardly extending pin 5 for connecting the frame to a draft vehicle, such as a road roller. The tank *d* is secured to the side bars by bands 6 which encircle the tank and which are suitably fastened to the bars. Handles 7 and 8 are se-

cured to each of the side bars. As shown, each handle 7 is secured to a side bar adjacent the tank *d* and extends forwardly and thence inwardly, and is secured to the central portion of the part 3^a of the bar, and each handle 8 is secured to said central portion of the part 3^a and extends forwardly and then inwardly at a right angle and joins the part 3^b of the bar. By means of these handles the vehicle may be manually moved when desired.

Between the converging parts 3^a of the side bars and adjacent the forward end of the tank *d* is arranged an upright cylindrical pressure tank *e*, adapted to contain air under pressure. The tank *e* is supported by two pairs of depending rods 9 and 10, the rods of each pair being connected to one of the side bars at the front and rear of the tank, the lower ends of each pair of rods being connected to the lower end of the tank by the same fastening bolt or device 11, so that the rods not only support the tank, but form diagonal braces for preventing forward or backward swinging of the lower end of the tank. The tank *e* is held in upright position against the forward end of the tank *d* by saddles 12, secured to the parts 3^a of the side bars. The tank *e* extends downwardly to a short distance from the ground, and when the cart or vehicle is not in motion or attached to a tractor, this tank forms a convenient rest or support for holding the cart with the tank *d* in horizontal position, which may be done by placing a block or stone of suitable size under the tank *e*. The tank *e* is provided with an inlet pipe or nipple 13, fitted with a suitable check valve, and it is also provided with an outlet pipe 14 having a branch 14^a which leads into the upper part of the tank *d*, through a reducing valve 15 and a manually controlled valve 16. The branch 14^a is connected to the pipe 14 at a point between the tank *e* and a manually controlled valve 17. By closing the valve 17 and opening the valve 16, air at reduced and substantially uniform pressure may be admitted to the tank *d* from the tank *e*, and by opening the valve 17, air at high pressure will flow from the tank *e* through the pipe 14 and valve 17, and this current of air under high pressure is utilized to clear the nozzles, as herein-after explained.

A pipe 18 extends transversely of the rear end of the tank *d*. This pipe is horizontally

arranged and is suitably secured to the end of the tank. The pipe 18 is connected at its central portion with a short downwardly turned pipe 19 within the tank *d*, the pipe 19 forming the outlet pipe for the tank, the open end of this pipe being arranged near the bottom of the tank *d*. Upon the ends of the pipe 18 are arranged elbow couplings 20 which may turn upon said pipe. Short pipes 21, of equal length, are provided with elbows 22 which are secured tightly on said pipes, but which are connected to the elbow 20 so that the elbows 22 may turn with respect to the elbows 20. The rear ends of the pipes 21 are provided with elbows 23 which are secured rigidly to said pipes, but are connected to a nozzle pipe 24 in such manner that they may turn with respect to said latter pipe. It will be seen that the pipes 18 and 24 are parallel, as are also the pipes 21, the system of distributing pipes constituting a parallelogram, and it will be evident that because of the swivel connections just described, the nozzle pipe 24 may be moved to one side or the other of its central position, as indicated in dotted lines in Fig. 1, always remaining parallel with the pipe 18 and with the roadway, and that it may also be swung upwardly so as to rest upon the tank *d*, as indicated in dotted lines in Fig. 2. The pipe 24 is connected to the top of the tank *d*, on the central line of the latter, by a flexible connection such as the chain 25, which holds the nozzle pipe at the proper distance from the ground when said pipe is lowered. This chain does not interfere with the lateral swinging of the nozzle pipe, although when said pipe is moved laterally from its central position, the chain connection will cause it to rise slightly, but not enough to interfere with the proper spreading of the material.

The nozzle pipe is provided with a series of nozzles 26, each nozzle having a suitable valve, and to the stems of the valves are connected valve levers 27. The valve levers are pivotally connected to a valve operating rod *f*, which is composed of two sections 28 and 29 connected by a latch 30. Hand levers 31 are connected to the opposite ends of this rod. It will be evident that when the two sections are connected by the latch 30, all of the nozzle valves may be operated together by means of one of the hand levers 31, and that by disconnecting the latch 30, one half of the nozzles may be controlled independently of the other half. This arrangement, as will be obvious, permits of delivering wide or narrow streams of material upon the roadway, and the lateral adjustment of the nozzle pipe permits of spreading the material directly over the path traversed by the vehicle, or at one side or the other of the vehicle.

65 The nozzle pipe 24 is provided on its

upper side with a valve controlled nipple 32 to which is connected a short section of hose 33, and the high pressure air pipe 14 is fitted with a short hose extension 34, the hose extensions 33 and 34 having suitable 70 couplings at the ends for connecting the two sections together. When the distributing pipes are swung upwardly, as indicated in dotted lines in Fig. 2, the hose couplings may be brought together and thus the nozzle pipe will be connected directly with the high pressure air pipe 14, and upon opening the valve 17, air under the full pressure in the tank *e* will flow into the nozzle pipe and blow out any sediment or material which 80 may remain in the nozzles.

In operation the tank *e* is filled with hot fluid road-binder or material and simultaneously the tank *e* is filled with compressed air. When the cart is brought into position 85 for use in the nozzles need clearing, the valve 17 is opened and air under high pressure passes through the nozzles. The hose couplings may then be disconnected and the distributing pipes lowered to working position and adjusted laterally to the desired position with respect to the roadway. The valve 16 is then opened and air at a reduced and uniform pressure is thereby admitted to the tank *d* and the fluid is thereby forced 90 into the distributing pipes. The fluid will therefore flow out of such nozzles as the operator may open. When the tank is empty the operator swings the nozzle pipe upward and any fluid remaining in the distributing 100 pipes and nozzles will flow backwardly into the tank *d*. Should any of this material remain in the nozzles and nozzle pipe, it may be blown out by high air pressure before the nozzles are lowered to discharge the next 105 tank load.

Ordinarily the material will be blown out of the tank before it has cooled; but occasionally, where the tank is left partly filled for a long time, the material will become 110 cool and sluggish, and in such cases it is desirable to apply heat to the tank in order to liquefy the material. For this purpose a fire or heater may be placed under the tank *d* until the material is sufficiently liquefied. Should the operator through carelessness apply too much heat to the tank, the curved portion of the axle *c* might sag under the weight of the tank, and to prevent this sagging I provide two rods 36 and 37, which 115 pass over the top of the tank *d* and have their ends secured to clips 38 beneath the horizontal portions of the axle, which portions are never over-heated. The bands referred to support the axle sufficiently to prevent the central part of the axle from sagging under the weight of the tank if said part becomes over-heated.

In Figs. 5, 6, and 7, I have shown a system of distributing pipes adapted for vehicles in 120 130

which the liquid holding tank is supported at a greater distance from the ground than is shown in the previously described figures. In Figs. 5, 6, and 7, the pipes are also arranged in the form of a parallelogram and with swiveled connections so that the nozzle pipe may be adjusted endwise, or at right angles to the path of movement of the vehicle, and may also swing vertically, remaining parallel with the axes of the wheels at all times. In these views the tank for containing the liquid is shown at d' , the transverse outlet pipe is shown at 18^a , the connecting pipes at 21^a , and the nozzle pipe at 24^a , the latter, in this instance, being indicated as a pipe having a rectangular section. Elbow joints 40 are swiveled to the ends of the outlet pipe 18^a , and the connecting pipes are suspended from these elbows by elbow couplings 41, which have swiveled connections with the elbows 40, and at the lower ends of the connecting pipes are elbows 42 which have swiveled connections with the nozzle pipe 24^a .

It will be evident from this construction that the nozzle pipe may be adjusted laterally parallel with the axes of the wheels, or at right angles to the path of movement of the vehicle, and also parallel with the roadway and that the nozzle pipe may be swung upwardly about the outlet pipe as an axis. It will be understood that the nozzle pipe will be supported in its working position by the chain or other flexible connection, as shown in the figures of the drawing first described.

What I claim is:

1. In a machine of the class described, the combination with a pair of wheels having a common axis, of a tank carried thereby, a horizontally disposed nozzle pipe, a fixed support, a pair of parallel connecting pipes having at one end swiveled connections with said nozzle pipe, and at their other end swiveled connections with said support, said connecting pipes being in communication with said tank and serving to convey material therefrom to said nozzle pipe, and said connecting pipes and swiveled connections permitting lateral movement of the nozzle pipe relative to the planes of the wheels, while maintaining said nozzle pipe always substantially parallel with the axis of such wheels.

2. In a distributor for liquid road material, a pair of wheels, a tank supported thereon, a fixed outlet pipe, means for feeding material from said tank to said pipe at a point intermediate its ends, a nozzle pipe, parallel connecting pipes between the ends of said fixed outlet pipe and said nozzle pipe, and swiveled joints between the connecting pipes and said outlet and nozzle pipes, said connecting pipes and swiveled joints permitting lateral movement of the

nozzle pipe relative to the planes of the wheels, while maintaining said nozzle pipe always substantially parallel with the axes of such wheels.

3. In a distributor for liquid road material, a pair of wheels, a tank supported thereon, an outlet pipe extending parallel with the axes of the wheels, a nozzle pipe, parallel connecting pipes between the outlet and nozzle pipes, and swiveled connections between the connecting pipes and the outlet and nozzle pipes, said connecting pipes and swiveled connections permitting lateral adjustment of the nozzle pipe with respect to the planes of the wheels and maintaining said nozzle pipe substantially parallel with the axes of the wheels in all positions of lateral adjustment.

4. In a distributor for liquid road material, a pair of wheels, a tank supported thereon, an outlet pipe, a nozzle pipe, parallel connecting pipes between the outlet and nozzle pipes, and swiveled connections between the connecting pipes and the outlet and nozzle pipes, said connecting pipes and swiveled connections permitting lateral adjustment of the nozzle pipe with respect to the planes of the wheels and maintaining said nozzle pipe substantially parallel with the axes of the wheels in all positions of lateral adjustment and also permitting the nozzle pipe to swing vertically.

5. In a distributor for liquid road material, a pair of wheels, a tank supported thereby, a fixed horizontal outlet pipe connected to the tank and extending parallel with the axes of the wheels, a nozzle pipe, parallel connecting pipes having swiveled connections with the ends of the outlet pipes, and swiveled connections between said connecting pipes and the nozzle pipe, said connections permitting the nozzle pipe to move laterally parallel with the outlet pipe and also to swing vertically.

6. In a distributor for liquid road material, a pair of wheels, a tank supported thereon, a horizontally extending outlet pipe connected with said tank, a pair of parallel connecting pipes extending downward from said outlet pipe, a nozzle pipe suspended by said connecting pipes, and extending parallel with said outlet pipe, and swiveled connections between the said outlet pipe and the upper ends of said connecting pipes, and between the said nozzle pipe and the lower ends of said connecting pipes, whereby said nozzle pipe may swing laterally relative to the planes of the wheels.

7. In a distributor for liquid road material, a wheeled vehicle, a liquid holding tank carried thereby, a nozzle pipe connected with the tank and arranged to swing relative thereto into inoperative position, a source of fluid pressure, a pipe connection extending from said source and terminating adjacent

the said inoperative position of the nozzle pipe, and means for coupling said pipe connection directly to said nozzle pipe when the latter is swung into such position.

8. In a distributor for liquid road material, a wheeled vehicle, a liquid holding tank carried thereby, a nozzle pipe connected with the tank and arranged to swing vertically relative thereto into an elevated position, a source of fluid pressure, a pipe connection extending from said source and terminating adjacent the said elevated position of the nozzle pipe, and means for coupling said pipe connection directly to said nozzle pipe when the latter is raised into such position.

9. In a device of the class described, the combination with a tank, of a nozzle pipe

connected therewith, a series of nozzles carried by said pipe, a valve for controlling each nozzle, a lever secured to each valve, a pair of aligned bars to each of which a plurality of said levers are pivotally connected, thus forming two groups, an operating lever secured to each bar, and means for connecting and disconnecting at will the adjacent ends of said bars, whereby the said groups of valves may be coupled for simultaneous operation, or operated separately.

In testimony whereof I affix my signature, in presence of two witnesses.

WILLIAM H. GAILOR.
